FRANCIS WATKINS, OF BIRMINGHAM, ENGLAND.

Letters Patent No. 84,782, dated December 8, 1868; patented in England December 28, 1866.

IMPROVEMENT IN BOLT-MAKING MACHINES.

The Schedule referred to in these Letters Patent and making part of the same.

To all whom it may concern:

Be it known that I, FRANCIS WATKINS, of Birmingham, in the county of Warwick, England, have invented a new and improved Machine for Forging and Shaping Rivets, Screw-Banks, &c.; and I do hereby declare that the following is a full, clear, and exact description thereof, which will enable those skilled in the art to make and use the same, reference being had to the accompanying drawings, forming part of this specification, in which—

Figure 1, sheet 1, represents a side elevation, partly in section, of my invention.

Figure 2, sheet 1, represents a vertical transverse section of the same, the plane of section being indicated by the line *x x*, fig. 3.

Figure 3 is a plan or top view of the same.

Figure 4 is a detail sectional view of the same, on an enlarged scale, the plane of section being indicated by the line *y y*, fig. 3.

Similar letters of reference indicate corresponding parts.

This invention relates to a new machine for heading rivets, screw-banks, and other bars, when the same are prepared in pieces of the required length.

The machine is so made that two sets of heading-devices are in constant operation, a head being formed alternately on each machine, so that the power required for one machine is utilized to operate two.

The invention consists chiefly in the use of two rotating disks mounted at the ends of a shaft, on which shaft is also placed and keyed a ratchet or feed-wheel, worked by a slotted rod, which is pin-jointed to a lever, acted on by a cam on another shaft.

In the periphery of each of the disks or die-carriers are placed dies for receiving the shanks or necks of the rivets, bolts, screw-banks, or other articles to be headed.

Inside of these dies are "tippers" or sliding bolts, for holding the blanks to their work, and for discharging the same when finished.

These tippers perform their work by means of their inner ends being cranked and resting in the grooves of a stationary cam, one such cam being arranged within each rotating disk.

The tippers are or may be made of two pieces, screwed together, so that they may be adapted to hold blanks of various lengths to be headed.

The two sides of the machine are alike, but the dies in the disks are arranged so that blanks are headed alternately on one and on the other side; or the disks are hung on separate shafts, which receive, alternately, intermittent rotary motion, by means of the slotted rods, working in the ratchet-wheels, of which, in the latter case, two are used, one on each shaft.

The rods or bars of metal are heated in a suitable furnace, and are then cut into pieces of the required length by suitable mechanism, which may, if desired, be attached to this machine.

These cut-off portions or blanks are placed into the

dies formed in the rotating disks, and as each blank arrives opposite the reciprocating heading-tool, the motion of the disk is arrested, and the heading-tool is caused to advance by suitable mechanism, and to press that portion of the blank which projects from the periphery of the disk into a head of the required form.

The heading-tool can be removed, so that it may be replaced by one having a different form, so that heads of any suitable or desired shape may be formed on this machine.

When the head is formed on a blank, the motion of the disk is resumed, and the next blank is brought into position to be headed.

While one disk is stationary, and its heading-tool in motion, the opposite disk is moved to bring a blank in position, but the other heading-die does not begin to move until the first has finished its work.

Thus, although one head is only formed at once, two machines are in constant, unceasing operation, and the same power which would be required to drive one machine is utilized to drive two, without loss of time to either.

When a blank has been headed, it is gradually pushed out by the "tippers," and is finally ejected when it arrives below the axis of the disk.

In the accompanying drawings—

A represents the frame of the machine.

B is a horizontal driving-shaft, on which are fastened a pinion, *a*, a fly-wheel, *b*, and a suitable driving-pulley.

The pinion *a* meshes into the teeth of a gear-wheel, *c*, and thus drives a shaft, *C*, on which the gear-wheel *c* is mounted.

On the ends of the shaft *C* are mounted two cams, *D* and *D'*, whose object is to actuate the slides *E* and *E'* respectively, in the ends of which the heading-tools *F* *F'* are held.

The cams *D* *D'* are of equal shape, but are made to project from opposite sides of the shaft *C*, so that the slides *E* *E'* are actuated alternately; that is, one slide moves forward while the other moves back, and *vice versa*.

The heading-tools are held by means of screws, pins, or otherwise, in their respective slides, and can be removed and replaced whenever desired.

In the face of each heading-tool is a cavity of the required form, as is clearly shown in fig. 4.

G is a stationary horizontal shaft, having its bearings in the frame *A*.

Around this shaft *G* are arranged two tubular axles, *H* and *H'*, each one surrounding about one-half the length of the shaft *G*.

Each axle *H* *H'* carries a ratchet-wheel, *d* *d'*, as shown, and a disk, *I* *I'*, at its end.

Upon the shaft *C* are mounted two eccentrics, *e* and *e'*, which are opposite to and in line with the wheels *d* and *d'*.

A ring, *f* *f'*, is laid around each cam, *e* *e'*, and is connected with a rod, *g* *g'*, having a hook formed at its end,

said hook resting upon the ratchet-wheel, opposite the cam, so that, as by the revolution of the shaft C the rod *g* is drawn back, the hook, which catches over a tooth on the ratchet-wheel, will carry the axle H or H' partly around, and thus intermittent rotary motion is imparted to the axles H H'.

The cams *e e'* are alike, but are set in different positions upon the shaft C, so that only one axle, H or H', is moved at once, while the hook *g* of the other axle moves forward to catch another tooth of its ratchet-wheel.

Each disk I I' has an outward-projecting flange, *h*, around its periphery, in which a series of radial perforations is arranged.

Into each of these perforations is placed a tubular tool, *i*, having a head, *i'*, which may project from or be countersunk in the edge of the disk, as is clearly shown in fig. 4.

These tools *i* may be arranged removably, so that they may be adapted to blanks of various diameters.

Their heads are of such form that they will impart the required shape to the neck of the blank.

J J' are two cams, mounted respectively on the ends of the stationary shaft G, so as to be outside of the face of each disk, and within the flange *h* of the same, as shown in figs. 1 and 4.

In the inner face of each cam *J J'* is arranged a groove, as shown in fig. 4, into which flanges, projecting from blocks *j j'*, are fitted, as shown.

Of the blocks *j*, an equal number is provided in each disk as there are tools *i i'* in the same.

To each block *j* is screwed or otherwise fastened a bar or rod, K, reaching into one of the tubes *i*, as shown.

As the disk rotates, the rods K and blocks *j* are carried around with it, and as they also move in the grooves of the cams *J J'*, they are gradually pushed out and drawn in.

The number of the teeth of the ratchet-wheels *d d'* is equal to that of the perforations in each disk, and they are so arranged that when a move of the hollow shaft carrying the disk is completed, a tool, *i*, will be opposite to the heading-tool.

Then the heading-tool is moved towards the disk, and is drawn back again, and not until then does the disk begin to move again.

Having described the construction, I will now proceed to describe the operation of the machine.

The machine being in motion, the blanks, which are cut, from a rod of the required thickness, into the required lengths, are placed, by hand or machinery, into those perforations of the disk which are at the time above the axis of the same.

As the machine is in motion, other perforations will continually arrive at the top, and are thus filled.

The lengths of the rods K are adjusted so that the required portion of the blank projects from the tool *i*, when the same arrives opposite to the heading-tool F or F'.

As the latter moves towards the disk it presses this projecting portion of the blank into the required form, so that a head and shoulder of the required shape are formed on the blank, as is clearly indicated in figs. 1 and 4.

The disk is then revolved again to bring up the next blank, and the same motion partly ejects the finished blank from its holder *i*, which ejection is wholly effected when it arrives at the under side of the disk.

The tool *i*, thus emptied, is then free to receive another blank.

The disks I I' may also, if desired, be mounted on one shaft.

In that case their perforations would be arranged in different positions, and the ratchet-wheel would receive as many teeth as there are perforations in both disks, so that each motion of the shaft would bring a blank in one of the disks against the heading-tool.

If desired, the disks may also be arranged so that blanks are being headed simultaneously in both, but it is evident that in that case nearly double the power would be used.

I claim as new, and desire to secure by Letters Patent—

The arrangement, herein shown and described, of two bolt-heading machines, constructed substantially as described, and so as to operate alternately, as set forth.

F. WATKINS.
